United States Patent Office.

JAMES E. EMERSON, OF TRENTON, NEW JERSEY.

Letters Patent No. 96,211, dated October 26, 1869.

IMPROVED ROCKING-CHAIR.

The Schedule referred to in these Letters Patent and making part of the same

To all whom it may concern:

Be it known that I, JAMES E. EMERSON, of Trenton, in the county of Mercer, and State of New Jersey, have invented certain new and useful Improvements in Rocking-Chairs; and I do hereby declare the following to be a full, clear, and exact description of the same, reference being had to the accompanying drawings, making a part of this specification, in which—

Figure 1 represents a perspective view of the rocking-chair;

Figure 2 represents a vertical section through the same.

Similar letters of reference, where they occur in the separate figures, denote like-parts of the chair in both of the drawings.

My invention relates to that kind of rocking-chair in which the upper or seat-portion rocks upon the stationary under or supporting-portion, and of which there are many forms; and

My invention consists in the devices by which the seat and base are united, and on which the seat-portion rocks.

And it further consists in the use of pivot-points and steps, for the seat to rock upon, which steps may also serve for oil-boxes, if oiling should be found necessary.

To enable others skilled in the art to make and use my invention, I will proceed to describe the same with reference to the drawings.

A represents the stationary under portion of the chair, which may be constructed in any of the usual well-known and substantial ways, and which I prefer to make rounded or circling on top, so that a circular concave seat will fit and move over it, the joint between the two being covered by a moulding, *a*, which prevents the clothes of the user from being caught therein, or from pinching the fingers.

The upper portion B of the chair, which consists of the seat *b*, arm-supports *c c*, and back *d*, may be made, and upholstered, if so desired, in any of the usual well-known ways, the side-pieces being, however, curved out, so as to snugly fit over the rounded part of the stand or stationary under portion.

On the rail or rung-pieces of the under stationary portion A, there are arranged steps, *e e*, which are cast with depressions or recesses in them, as shown by the dotted lines thereon, which form boxes, and in which the projecting points on the ends of the V or U-shaped supports C C, that are fastened to the upper or seat-portion B of the chair, enter and are supported, and upon which points, like the "knife-edge" of a scale-beam, the seat-portion rocks.

In the supports or braces C are made circular slots, *ff*, through which a screw, stud, or pin, *i*, is passed

into the plate that margins the steps, which connection admits of the rocking of the seat-portion upon the points in the steps, and without a pivot-pin to work on, and still unite the upper and under portions, so that the chair may be moved about without the two parts separating.

Should it become necessary at any time to oil the bearing-points on which the seat rocks, it may be done without liability of oiling or soiling the carpet or floor, as the steps are boxes capable of holding a drop or more of oil without allowing it to escape.

From the upper cross-piece D of the stationary portion A, a coiled spring, E, extends to and bears against the front piece F of the seat-portion, the reaction of which spring moves or helps to move the upper portion in one direction, whilst its compression prevents the seat from going too far, or with a jar, in the other direction.

This spring may extend from D to the rear piece G, and serve the same purpose, or there may be two springs, one front and the other back, but one will be found to be enough.

If the chair is required for a stationary or a reclining-chair, it may be made either by means of a spring-bolt, *m*, with a thumb-nut head, *n*, which will take into any one of a series of holes, *o o o*, in the seat-portion, and there hold it firmly to the stationary under portion.

The bolt passes through a catch-piece, *r*, that has recesses or notches *s* in it, so that the bolt in being turned will draw out and be caught and held out, when used as a rocking-chair, and can be turned further, when it will shoot into one of the holes *o*, and then hold it rigid and in an inclined position, when so desired.

Having thus fully described my invention, What I claim therein as new, and desire to secure by Letters Patent, is—

The combination of the pivot-pieces or supports C with the steps *e*, for forming a rocking connection between the upper and under portions of the chair, as described and represented.

Also, the combination of the pivot-pieces, steps, and spring, with the oscillating seat and stationary under portion, as and for the purpose herein described and represented.

Also, in combination with the pivot-pieces and steps, the concentric slot and set-screw, for admitting of the rocking motion of the upper upon the under portion, without allowing them to separate when being lifted or carried, as set forth.

J. E. EMERSON.
